WATER TUBE BOILER HAVING STEAM
SUPERHEATER INTERCHANGEABLE TO
FEED PREHEATERMiyokichi Ikeda, Okubo, Yodobashiku,
Tokyo, JapanApplication June 27, 1933, Serial No. 677,822
In Japan October 1, 1932

3 Claims. (Cl. 122—478)

My invention relates to improvements in water tube boilers, more particularly to an improved combination of a steam superheater interchangeable to a feed preheater with a specially arranged multiple drum water tube boiler, and has for its object the provision of a very simple and effective arrangement of water tube boilers which will generate the superheated steam and which can also be easily converted into an ordinary water tube boiler generating a greater amount of high pressure steam for special purposes.

Water tube boilers having multiple drums such as three or four drums arranged in triangular or quadrilateral relation and connected together by means of water tubes amount to much less in total height if compared with the other type of multi-drum boilers, and there is a large vacant space left on the top. Accordingly if such space is taken advantage of by installing a steam superheater the space for a complete boiler unit can be greatly economized. In accordance with this invention the above described vacant top space of a water tube boiler having three or four main drums arranged in triangular or quadrilateral relation is utilized to receive a special steam superheater interchangeable to a feed water preheater directly associated with the main boiler.

For the consideration of what I believe to be novel and my invention, attention is directed to the following specification and the claims appended thereto. In the accompanying drawing, Figure 1 is a diagrammatic sectional elevation illustrating the arrangement of a water tube boiler embodying this invention. Figure 2 is a view in similar position of a modification.

Referring more in detail to the drawing, A represents a main water tube boiler assembly or unit having drums 1, 2, 2' and 3 connected together with water tubes 4, 5, 6 and 7 respectively. The drums 2 and 2' may sometimes be combined into a single drum 2" as shown in Figure 2. However, an auxiliary steam drum 1' is connected to the main steam drum, but it may be omitted if desired. On the other hand, B represents the steam superheater unit embodying this invention, which may be converted into a feed water preheater. The combined superheater and feed water preheater comprises a front drum 8 located above and parallel to the top drum or main steam drum 1 of the water tube boiler A and a rear drum 9 placed above the auxiliary steam drum 1', if the latter is provided. The drum 9 is divided into two compartments by means of a longitudinal partition wall 10 and each resulting compartment is connected to the front drum 8 by means of

water tubes 11 and 12 which are preferably curved outwardly. The lower compartment of the drum 9 is connected to the steam drum 1' or to the steam drum 1 if there is no auxiliary drum 1' through a pipe 13 and a stop valve 14 and also connected to the feed water pipe 15 through a stop valve 14', while the upper compartment of the drum 9 communicates with the superheated steam supply pipe 17 through a stop valve 16 and also connected to a suitable drum such, for instance, as 2' of the main boiler A through a check valve 18 and a feed water pipe 19. The superheater unit B is associated with the main boiler A on top of the latter to cooperate with it, while a suitable combustion grate 20 such as an automatic stoker; 21 represents the combustion chamber; 22, 23 and 24 designate baffle walls, and 25 represents the outlet for the combustion gases.

The passage of flame in the combustion chamber of the present boiler is as shown by the arrows and the tube nests 11 and 12 of the superheater B are heated by the gases of the combustion which have passed through the main boiler. When the element B is used as a steam superheater the valves 14' and 18 should be closed and the valves 14 and 16 are opened to supply the steam in the steam drum 1' into the lower compartment of the drum 9. Then the steam passes through the tube nest 11 into the opposite drum 8 and through the tube nest 12 enters into the upper compartment of the drum 9, and the superheated steam is delivered through the valve 16 to the supply pipe 17. If the element B is to be used as a feed water preheater, the valves 14 and 16 should be closed and the valves 14' and 18 are opened so that the feed water is supplied to the lower compartment of the drum 9 from the feed water pipe 15 so that it passes through the tube nest 11 into the drum 8 and is delivered into the upper compartment of the drum 9 through the tube nest 12. Thus the preheated water is supplied to the drum 2' through the valve 18 and the pipe 19, and ordinary high pressure steam may be sent out of the drum 1' through an outlet 17' for this purpose. In this manner, the unit B may conveniently be converted into a feed preheater from a steam superheater and it will be seen that the unit B can be easily installed upon the main boiler A and it has a simple construction which facilitates cleaning and repair without disturbing the main boiler.

What I claim as new and desire to secure by Letters Patent of the United States, is,—

1. A steam generator system comprising in 55

combination, a water tube boiler having at least three spaced drums interconnected in a continuous closed circuit or series by means of groups of steam tubes, one of which drums is a boiler steam drum disposed at a higher level than the other drums, a steam superheater wholly spaced over said boiler and comprising two spaced steam superheater drums, of which one superheater drum is disposed at a higher level than the other 10 superheater drum and subdivided by means of an interior partition into a pair of separate upper and lower steam chambers which are each connected by steam tubes with said other superheater drum, means including a valve controlled pipe 15 connecting said boiler steam drum with the lower steam chamber of said subdivided superheater drum, there being a valve controlled feed water main connected to said steam generator system for supplying water to at least a portion of said 20 system at will, and a steam outlet main connected to the upper steam chamber of said subdivided superheater drum, there being means for simultaneously heating said water tube boiler and steam superheater, an auxiliary steam drum 25 disposed over the boiler and forming part of the means connecting the boiler steam drum with the lower steam chamber of the subdivided superheater drum and being connected between the boiler steam drum and the valve control in said connecting means, and an auxiliary steam outlet main connected to said auxiliary steam drum.

2. A steam generator system comprising in combination, a water tube boiler having at least three spaced drums interconnected in a continuous closed circuit or series by means of groups of steam tubes, one of which drums is a boiler steam drum, disposed at a higher level than the other drums, a steam superheater wholly spaced over 30 said boiler and comprising two spaced steam superheater drums, of which one superheater drum is disposed at a higher level than the other superheater drum and subdivided by means of an interior partition into a pair of separate upper and lower steam chambers which are each connected by steam tubes with said other superheater drum, means including a valve controlled pipe connecting said boiler steam drum with the lower steam chamber of said subdivided superheater drum, there being a valve controlled feed water main 35 connected to said steam generator system for supplying water to at least a portion of said system at will, and a steam outlet main connected to the upper steam chamber of said subdivided superheater drum, there being means for simultaneously heating said water tube boiler and steam superheater, an auxiliary steam drum also disposed over the boiler and connected to the valve controlled pipe included in the means connecting the boiler steam drum with the lower steam chamber of the subdivided superheater drum, and interposed between the boiler steam 40 drum and the valve control in said pipe, which means also include a steam connection between said boiler steam drum and said auxiliary steam drum, the valve controlled feed water main being connected to the lower steam chamber of said subdivided superheater drum, an auxiliary steam outlet main connected to said auxiliary steam drum, and a valve controlled pipe connecting one of the boiler drums which is disposed below the 45 level of the boiler steam drum with the upper steam chamber in said subdivided steam drum of said steam superheater.

for simultaneously heating said water tube boiler and steam superheater, an auxiliary steam drum disposed over the boiler and forming part of the means connecting the boiler steam drum with the lower steam chamber of the subdivided superheater drum and being connected between the boiler steam drum and the valve control in said connecting means, the valve controlled feed water main being connected to the lower steam chamber of said subdivided superheater drum, and an auxiliary steam outlet main connected to said auxiliary steam drum. 5

3. A steam generator system comprising in combination, a water tube boiler having at least three spaced drums interconnected in a continuous closed circuit or series by means of groups of steam tubes, one of which drums is a boiler steam drum, a steam superheater wholly spaced over 15 said boiler and comprising two spaced steam superheater drums, of which one superheater drum is subdivided by means of an interior partition into a pair of separate upper and lower steam chambers which are each connected by steam tubes with said other superheater drum, means including a valve controlled pipe connecting said boiler steam drum with the lower steam chamber of said subdivided superheater drum, there being a valve controlled feed water main 20 connected to said steam generator system for supplying water to at least a portion of said system at will, and a steam outlet main connected to the upper steam chamber of said subdivided superheater drum, there being means for simultaneously heating said water tube boiler and steam superheater, an auxiliary steam drum 25 also disposed over the boiler and connected to the valve controlled pipe included in the means connecting the boiler steam drum with the lower steam chamber of the subdivided superheater drum, and interposed between the boiler steam drum and the valve control in said pipe, which means also include a steam connection between said boiler steam drum and said auxiliary steam drum, the valve controlled feed water main being 30 connected to the lower steam chamber of said subdivided superheater drum, an auxiliary steam outlet main connected to said auxiliary steam drum, and a valve controlled pipe connecting one of the boiler drums which is disposed below the 35 level of the boiler steam drum with the upper steam chamber in said subdivided steam drum of said steam superheater. 40
